UNITED STATES PATENT OFFICE.

RONALD A. McCANN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed October 6, 1923. Serial No. 666,952.

My invention relates to railway traffic controlling apparatus, and particularly to apparatus of the type wherein governing mechanism on a train is controlled by energy received inductively from the track rails. More particularly the present invention relates to the trackway portion of such apparatus.

I will describe two forms of apparatus embodying my invention, and will then point out the novel features thereof in claims.

In the accompanying drawings, Fig. 1 is a diagrammatic view showing one form of trackway apparatus embodying my invention, and Fig. 2 is a diagrammatic view showing a modification of the apparatus shown in Fig. 1 and also embodying my invention.

Referring first to Fig. 1, the reference characters 1 and 1^a designate the track rails of a railway along which traffic normally moves in the direction indicated by the arrow. These rails are divided by insulated joints 2 into a plurality of successive sections of which only one section D—E is shown in the drawings. It is understood, however, that each section would be provided with apparatus similar to the apparatus associated with the section D—E.

In the form here shown, the railway is of the electric propulsion type, so that balanced inductive bonds 3 are provided to conduct the propulsion current around the insulated joints 2.

Track circuit current is normally supplied to the rails at the exit end of section D—E by a transformer T², the secondary of which is constantly connected across the track rails. The primary of this transformer is provided with a circuit which passes from a wire B, through front point of contact 5 of relay F, primary of transformer T² and front point of contact 6 of relay F to a wire C. Wires B and C are constantly supplied with alternating current by a generator G. Relay F is controlled by a front contact 4^a of a track relay R³ for the section next in advance of section D—E, so that when such section next in advance is unoccupied relay F is energized and alternating current of what I will term "normal" relative polarity is then supplied to section D—E at the exit end of the section.

When relay F is de-energized track circuit current is supplied to transformer T² under the control of a relay R². Relay R² is provided with a winding 24 which receives energy from the track rails through a transformer T³, the primary of which is connected across the rails at an intermediate point K in the section D—E. This point K is located at substantially maximum braking distance in the rear of point E for trains moving at a medium speed, such as 35 miles per hour. As here shown, relay R² is provided with a second winding 25 which receives energy from the track rails at the exit end E of section D—E. Both windings 24 and 25 must receive energy in order to energize relay R². When relay R² is energized and relay F is de-energized, the primary circuit for transformer T² passes from wire B, through front point of contact 10 of relay R², back point of contact 6 of relay F, primary of transformer T², back contact 5 of relay F, and front point of contact 9 of relay R² to wire C. When this circuit is closed, current of what I will term "reverse" relative polarity is supplied to the rails of section D—E at the exit end of the section.

Located adjacent the entrance end of section D—E is a slow-releasing relay L, the circuit for which passes from wire B through the back point of contact 10 of relay R², back point of contact 8 of relay F and winding of relay L to wire C. Relay L is therefore normally de-energized, and is energized only when both relays R² and F are de-energized.

Also located at the entrance end of section D—E is a track relay R' having two windings 17 and 18. Winding 17 is connected across the track rails in series with an impedance 16, whereas winding 18 is normally supplied with current in a manner which will be explained hereinafter. When relay L is de-energized, the impedance 16 is shunted through back contact 21, so that this impedance has no effect on the track circuit current supplied to relay winding 17. When relay L is energized, however, its back contact 21 is opened so that impedance 16 is effective to limit the amount of current supplied to relay winding 17.

Also located at the entrance end of section D—E is a transformer T', the secondary of which is connected across the rails of

the section. When relay L is de-energized, the primary circuit for transformer T' is opened at contact 23, but when relay L is energized, current is supplied to the primary of transformer T' through a circuit which passes from wire B, through contact 23 of relay L and the primary of transformer T' to wire C. The current which is then supplied to the track rails is of reverse relative polarity.

The supply of current to winding 18 of relay R' is controlled by relay L and by a pole-changing relay P. Pole-changing relay P is controlled by contact 7 of relay F, so that relay P is energized when relay F is energized, and de-energized when relay F is de-energized. When relay P is energized and relay L is de-energized, the circuit for winding 18 is from wire B, through front point of contact 19 of relay P, back contact 22 of relay L, winding 18 and front point of contact 20 of relay P to wire C. The current which is then supplied to winding 18 is of normal relative polarity. When relay P is de-energized and relay L is de-energized, the circuit for winding 18 is the same as before except that the current supplied to this winding is of reverse relative polarity due to the pole-changing action of contacts 19 and 20 of relay P. When relay L is energized, winding 18 is, of course, de-energized.

The reference character M designates a transformer the primary of which is connected across the wires B and C, and the secondary of which is connected with the middle points of the two inductive bonds 3 associated with section D-E. It will be seen, therefore, that the alternating current supplied by transformer M passes through the two track rails 1 and 1^a of section D-E in multiple, and that the supply of this current is constant. The current supplied by transformer M, I will term "local" current.

Before explaining the operation of the apparatus, it should be pointed out that the trackway apparatus herein shown is intended for co-operation with train-carried mechanism so designed that when a train receives track circuit current of normal relative polarity and also local current, a proceed indication is given on the train; when the train receives track circuit current of reverse relative polarity and also local current, a caution indication is given on the train; and when the supply of track circuit current is discontinued, a stop indication is given on the train.

As shown in the drawing, the apparatus is not affected by the presence of trains, so that track circuit current of normal relative polarity is supplied to the rails at the exit end of the section by transformer T². A train passing through the section in the direction indicated by the arrow will there-

fore receive track circuit current of normal relative polarity and also local current throughout the section, and so a proceed indication will be given aboard the train. As such train enters section D-E it will de-energize relay R', and as the train approaches point K it will also de-energize relay R², but neither of these relays will have any effect on the other parts of the apparatus. As the train passes point E it will place signal S² at stop, and will cause relay F to become de-energized thereby opening the normal primary circuit for transformer T². Relays F and R² being de-energized, relay L will become energized through back contact 8 of relay F and back contact 10 of relay R², and current will then be supplied to the primary of transformer T' through contact 23 of relay L. This current will energize relay R², whereupon the auxiliary primary circuit for transformer T² will become closed through contacts 9 and 10 of relay R² and back contacts 5 and 6 of relay F, so that track circuit current of reverse relative polarity will be supplied to the rails of section D-E at the exit end of this section. At the same time pole-changing relay P will become de-energized due to the opening of contact 7 of relay F, so that current of reverse relative polarity will be supplied to winding 18 of relay R', whereby the currents in the two windings 17 and 18 of relay R' are of the same relative polarity and the relay will therefore be energized.

I will now assume that the first train remains in the section immediately to the right of point E, and that a second train enters section D-E. As soon as such second train enters the section it will receive track circuit current of reverse relative polarity, so that a caution indication will be given aboard the train. As the second train approaches point K it will cause relay R² to become de-energized, thereby opening the auxiliary primary circuit for transformer T², so that the supply of track circuit current to the rails at the exit end of the section will be discontinued. It follows that a stop indication will be given aboard the second train from the point at which this train causes relay R² to open. Inasmuch as relays R² and F are now both de-energized, relay L will become energized, thereby closing the primary circuit for transformer T', opening the circuit for track relay winding 18, and opening the shunt around impedance 16 in the circuit for relay winding 17. Track circuit current of reverse relative polarity is then supplied to the track rails at the entrance end of section D-E, but winding 17 of track relay R' is protected from over-energization by impedance 16. As the second train passes out of section D-E track relay R² will become energized by track circuit current supplied from transformer

T' and the closing of relay R² will cause relay L to become de-energized. The opening of relay L opens the primary circuit for transformer T', closes the shunt around impedance 16, and also closes the circuit for relay winding 18. Track relay R² being energized, current of reverse relative polarity is again supplied to the track rails by transformer T², so that track relay R' becomes energized. When both trains pass out of the section immediately to the right of section D—E relay F again becomes energized, so that track circuit current of normal relative polarity is again supplied to the rails of section D—E, and all parts of the apparatus associated with this section are restored to their normal conditions.

While the first train is in the section to the right of point E and the second train is between points K and E, relay R² cannot become energized because track circuit current from T' is shunted away from winding 25 by the wheels and axles of the second train.

Referring now to Fig. 2, the apparatus shown in this view is the same as that shown in Fig. 1, except that the track relay R' at the entrance end of section D—E is of a single winding type, and except that contact 21 of relay L opens the circuit for relay R' instead of opening a shunt around an impedance in this circuit as in Fig. 1. That is to say, one terminal of relay R' is directly connected with the upper track rail 1, whereas the other terminal is connected with the lower track rail 1^a through back contact 21 of relay L. When relay L is energized so that track circuit current is supplied to the rails by transformer T', track relay R' is disconnected from rail 1^a, so that this relay is protected from over-energization. Inasmuch as the second winding is omitted from relay R', the pole-changing relay P is likewise omitted.

The operation of the apparatus shown in Fig. 2, will be understood from the explanation hereinbefore given of the operation of the apparatus shown in Fig. 1.

Apparatus embodying my invention is particularly well adapted for application to electrified roads of an automatic train control system of the type wherein two currents are normally supplied to the track rails and the supply of one current is discontinued at an intermediate point of a section in the rear of an occupied section. The two currents referred to are the track circuit and the local current, the former of which flows through the track rails in series and the latter of which flows through the track rails in multiple. On electrified roads it is undesirable to break the circuit for the local current at an intermediate point in the section, and it is also undesirable to insert insulated joints at such intermediate point

for the purpose of breaking the track circuit current. One feature of my invention is the provision of means for discontinuing the supply of track circuit current between points K and E in the rear of an occupied section without necessitating insulated joints in the track rails at the point K.

Although I have herein shown and described only two forms of apparatus embodying my invention, it is understood that various changes and modifications may be made therein within the scope of the appended claims without departing from the spirit and scope of my invention.

Having thus described my invention, what I claim is:

1. In combination, a section of railway track, means operating when the track ahead of said section is unoccupied to supply track circuit current to the rails at the exit end of the section regardless of traffic conditions in the section, and means operating when the track ahead of said section is occupied to supply track circuit current to the rails at the exit end of the section under the control of traffic conditions within the section.

2. In combination, a section of railway track, means operating when the track ahead of said section is unoccupied to supply track circuit current of one relative polarity to the rails at the exit end of the section regardless of traffic conditions in the section, and means operating when the track ahead of said section is occupied to supply track circuit current of the other relative polarity to the rails at the exit end of the section under the control of traffic conditions within the section.

3. In combination, a section of railway track, a relay controlled by traffic conditions ahead of said section, means operating when said relay is energized to supply track circuit current to the rails at the exit end of the section, a second relay receiving energy from the rails at an intermediate point in said section, and means for supplying track circuit current to the rails at the exit end of said section when said first relay is de-energized and said second relay is energized.

4. In combination, a section of railway track, means for supplying track circuit current across the rails at the exit end of said section, and means operating to discontinue such current supply when a train passes an intermediate point in said section and the track ahead of the section is occupied.

5. In combination, a section of railway track, a relay controlled by traffic conditions ahead of said section, means operating when said relay is energized to supply track circuit current to the rails at the exit end of the section, a second relay receiving energy from the rails at an intermediate point in said section, means for supplying track circuit

cuit current to the rails at the exit end of said section when said first relay is de-energized and said second relay is energized, and means operating when both of said relays are de-energized to supply track circuit current to the rails at the entrance end of the section.

6. In combination, a section of railway track, means operating when the track ahead of said section is unoccupied to supply track circuit current to the rails at the exit end of the section regardless of traffic conditions in the section, means operating when the track ahead of said section is occupied to supply track circuit current to the rails at the exit end of the section under the control of traffic conditions within the section, and means operating to supply track circuit current to the rails at the entrance end of said section when the track ahead of the section is occupied and a train is beyond an intermediate point in the section.

7. In combination, a section of railway track, means for supplying track circuit current to the rails at the exit end of said section, means operating to discontinue such current supply when a train passes an intermediate point in said section and the track ahead of the section is occupied, and means for supplying track circuit current to the rails at the entrance end of said section when the supply at the exit end is discontinued.

8. In combination, a section of railway track, means operating when the track ahead of said section is unoccupied to supply track circuit current of one relative polarity to the rails at the exit end of the section regardless of traffic conditions in the section, means operating when the track ahead of said section is occupied to supply track circuit current of the other relative polarity to the rails at the exit end of the section under the control of traffic conditions within the section, and means for supplying track circuit current of the last-mentioned relative polarity to the rails at the entrance end of the section when the track ahead of the section is occupied and a train occupies the section between an intermediate point and the exit end of the section.

9. In combination, a section of railway track, means for supplying track circuit current to the rails at the exit end of the section, and means operating when a train passes an intermediate point in said section and the track ahead of the section is occupied to discontinue such current supply and to supply current to the rails at the entrance end of the section.

10. In combination, a section of railway track, a relay controlled by traffic conditions ahead of said section, means operating when said relay is energized to supply track circuit current of one relative polarity to the rails at the exit end of the section, a second

relay receiving energy from the rails at an intermediate point in said section, means for supplying track circuit current of the other relative polarity to the rails at the exit end of said section when said first relay is de-energized and said second relay is energized, and means for supplying track circuit current of the last-mentioned relative polarity to the rails at the entrance end of said section when both of said relays are de-energized.

11. In combination, a section of railway track, a relay controlled by traffic conditions ahead of said section, means operating when said relay is energized to supply track circuit current to the rails at the exit end of the section, a second relay receiving energy from the rails at an intermediate point in said section, means for supplying track circuit current to the rails at the exit end of said section when said first relay is de-energized and said second relay is energized, a third relay normally de-energized but energized when the first and second relays are both de-energized, and means operating when said third relay is energized to supply track circuit current to the rails at the entrance end of said section.

12. In combination, a section of railway track, means operating when the track ahead of said section is unoccupied to supply track circuit current to the rails at the exit end of the section regardless of traffic conditions in the section, and means operating when the track ahead of said section is occupied to supply track circuit current to the rails at the exit end of the section or to discontinue such supply depending on traffic conditions within the section.

13. In combination, a section of railway track, means for supplying track circuit current to the rails at the exit end of said section, and means operating to discontinue such current supply when a train passes an intermediate point in said section and the track ahead of the section is occupied.

14. In combination, a section of railway track, both track rails of which are electrically continuous throughout the length of the section, means for supplying track circuit current across the rails at the exit end of the section when the track ahead of said section is unoccupied, and means operating when the track ahead of said section is occupied to supply track circuit current across the rails at the exit end of the section under the control of traffic conditions within the section.

15. In combination, a section of railway track, means operating when the track ahead of said section is unoccupied to supply track circuit current of one relative polarity to the rails at the exit end of the section, means operating when the track ahead of said section is occupied to supply track

5 circuit current of the other relative polarity to the rails at the exit end of the section under the control of traffic conditions within the section, a track relay having two windings one of which receives energy from the track rails at the entrance end of the section, and means for supplying the other winding of said relay with current of the same relative polarity as that supplied to the rails at the exit end of the section.

10 16. In combination, a section of railway track, a relay controlled by traffic conditions ahead of said section, means operating when said relay is energized to supply track circuit current of one relative polarity to the rails at the exit end of the section, a second relay receiving energy from the rails at an intermediate point in said section, means for supplying track circuit current of the other relative polarity to the rails at the exit end of said section when said first relay is de-energized and said second relay is energized, a track relay having two windings one of which receives energy from the rails at the entrance end of said section, a pole-changing relay controlled by the first-mentioned relay, and means controlled by said pole-changing relay for supplying current to said second winding of the same relative polarity as that supplied to the track rails.

15 17. In combination, a section of railway track, means operating when the track ahead of said section is unoccupied to supply track circuit current to the rails at the exit end of said section, a relay having two windings one of which receives energy from the rails at an intermediate point in said section and the other of which receives energy from the rails at the exit end of the section, means for supplying track circuit current to the rails at the entrance end of said section when the track ahead of said section is occupied and said relay is de-energized.

20 18. In combination, a section of railway track, means operating when the track ahead of said section is unoccupied to supply track circuit current to the rails at the exit end of said section, a relay having two windings one of which receives energy from the rails at an intermediate point in said section and the other of which receives energy from the rails at the exit end of the section, and means for supplying track circuit current to the rails at the entrance end of said section when the track ahead of said section is occupied and said relay is de-energized.

25 19. In combination, a section of railway track, a relay having two windings one of which receives energy from the rails at an intermediate point in said section and the

other of which receives energy from the rails at the exit end of the section, and means controlled by said relay for supplying train governing current to the rails of said section.

30 20. In combination, a section of railway track, a relay having two windings one of which receives energy from the rails at an intermediate point in said section and the other of which receives energy from the rails at the exit end of the section, and means controlled jointly by said relay and by traffic conditions in advance of said section for supplying train governing current to the rails of said section.

35 21. In combination, a section of railway track, a relay having two windings one of which receives energy from the rails at an intermediate point in said section and the other of which receives energy from the rails at the exit end of the section, and means operating to supply train governing current to the rails at the entrance end of said section when said relay is de-energized and the track ahead of the section is occupied.

40 22. In combination, a section of railway track, a relay receiving energy from the rails at an intermediate point in said section, and means controlled by said relay for supplying train governing current to the rails of said section.

45 23. In combination, a section of railway track, a relay receiving energy from the rails at an intermediate point in said section, and means controlled jointly by said relay and by traffic conditions in advance of said section for supplying train governing current to the rails of said section.

50 24. In combination, a section of railway track, a relay receiving energy from the rails at an intermediate point in said section, and means operating to supply train governing current to the rails at the entrance end of said section when said relay is de-energized and the track ahead of the section is occupied.

55 25. In combination, a section of railway track, means for supplying the rails of said section with alternating current of one relative polarity or the other, a relay having two windings one of which receives energy from the rails of said section, and means for supplying the other winding of said relay with alternating current of the same relative polarity as that of the current supplied to the rails of said section.

60 26. In combination, a section of railway track, means for supplying the rails of said section with alternating current of one relative polarity or the other, a relay having two windings one of which receives energy from the rails of said section, means for supplying the other winding of said relay with alternating current of the same relative

6
polarity as that of the current supplied to the rails of said section, and traffic governing means controlled by said relay.

27. In combination, a section of railway track, means controlled by traffic conditions in advance of said section for supplying alternating current of one relative polarity or the other to the rails of said section, a relay having two windings one of which re-

ceives energy from the rails of said section, and means controlled by traffic conditions in advance of said section for supplying the other winding of said relay with alternating current of the same relative polarity as that of the current supplied to the rails of said section.

In testimony whereof I affix my signature.
RONALD A. McCANN.
